UNITED STATES PATENT OFFICE.

HAYDEN H. TRACY, OF SAN FRANCISCO, CALIFORNIA.

HEAT-TRANSFERRING APPARATUS.

No. 839,082.

Specification of Letters Patent.

Patented Dec. 18, 1906.

Application filed February 15, 1906. Serial No. 301,303.

To all whom it may concern:

Be it known that I, HAYDEN H. TRACY, a citizen of the United States of America, residing at San Francisco, county of San Francisco, and State of California, have invented 5 certain new and useful Improvements in Heat-Transferring Apparatus; and I hereby declare the following to be a full, clear, and exact description of the same, reference being had to the accompanying drawings, forming a part of this specification.

This invention relates to certain improvements in apparatus for the transfer of heat, and is especially applicable to reheating devices interposed between the high and low 15 pressure cylinders of reciprocating steam-engines or in any case when steam or other elastic fluid is to be heated or reheated.

My improvements consist in a series or 20 tiers of pipes of thin section through which an elastic fluid to be heated or cooled is passed, these pipes being surrounded by and exposed to the temperature of another fluid, such as the furnace gases of combustion, and 25 consist especially in a means to cause a uniform flow of the liquid to be heated or cooled through the manifolds or tiers of pipes by adjusting their aggregated area so as to cause a uniform flow and distribution of the 30 steam or other fluid to be heated through all the pipes at a minimum velocity, and consequently permit the greatest possible transfer 35 of heat. The means employed to accomplish this purpose are very simple, consisting usually of a sliding register-damper, baffling-plate, or like devices to cover and reduce 40 equally the bare tubes at their ends, producing sufficient back pressure in the supply-pipes to cause a like flow in each tube of the 45 heater. A like result can be attained, but without adjustment, by inserting ferrules or bushing-collars in the tubes; but as the variations of pressure or volume and other circumstances of application may demand adjustment I adopt the devices shown in the drawings now to be hereinafter described.

To apply my invention in practice, I employ devices substantially as shown in the drawings herewith and forming a part of this 50 specification.

Figure I is an elevation, partially in section, of apparatus to illustrate my invention; Fig. II, a view, partially broken away, of the back of one of the junction-boxes; Fig. III, a 55 partial horizontal section through one of the

junction-boxes on the line *a* in Fig. I, and Fig. IV an end view of one of the tubes with a reducing-ferrule inserted.

1 is a chimney, flue, or other conduit for 60 hot gases and may be vertical or horizontal.

2 is a tier of heating-pipes connecting to and combined by the junction-boxes 3 and 4 and arranged in units of any required number.

5 is a supply-pipe through which passes 65 steam or other elastic fluid to be heated to the junction-box 3, and 7 a continuation of the pipe 5 for the fluid after it has passed through the pipes 2 in the direction indicated by arrows toward the outflow-pipe 7. 70

When the desired contraction of the tubes 2 is known or is determined by experiment for an unchangeable volume to be passed through them, their area can be reduced to the desired size by means of inserted collars 75 or ferrules 15, as shown in Fig. IV.

In the junction-box 3 I provide a sliding register-plate 8, having perforations 9, that correspond to the ends of the tubes 2, so arranged as to partially cover the latter, as 80 shown in Fig. II. This plate 8 as arranged is moved longitudinally by an oscillating shaft 10, operated by a handle 12, and is connected to the plate 8 by a crank 13 and link 14, as shown in Figs. II and III, but may be 85 operated in any suitable manner.

In operating as a heater between the high and low pressure cylinders of a steam-engine, the most common use of the apparatus, steam from the engine is discharged through the 90 pipe 5 into the junction-box 3. Contraction of the ends of the tubes 2, caused by the register or damper-plate 8, causes a slight back pressure and produces an equal flow of steam through all the tubes at a velocity as low as 95 the volume will permit.

Without the register-plate 8 or like means of controlling the area of the tubes 2 the steam would pass through them irregularly, tending to travel through the cooler tubes, 100 and the transfer of heat from the hot gases be less effective.

I have described my invention especially as applied to an interheater for multiple-cylinder expanding steam-engines; but it will 105 be obvious that it is alike applicable to any engine, also to cooling processes, as in air-compressing, and that the conduit 1 may contain a cooling fluid instead of hot gases.

Having thus described the nature and ob- 110

jects of my invention and a manner of applying the same, what I believe to be new, and desire to secure by Letters Patent, is—

In heat-transferring apparatus, a heating-chamber, headers on opposite sides of said chamber, a set of multiple tubes in said chamber, between said headers, connected with the latter and forming communication between them, an inlet-pipe for fluid to one header, an outlet-pipe to the other header, a register-valve in one header for regulating

the effective apertures of said multiple tubes simultaneously, and means for operating said valve, substantially as specified.

In testimony whereof I have signed my name to this specification in the presence of two subscribing witnesses.

HAYDEN H. TRACY.
